FRITZ SCHROETER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

METHOD TO CONTROL LIGHT RELAYS

Application filed April 18 1927, Serial No. 184,560, and in Germany May 20, 1926.

It is well known that by means of modulated high-frequency oscillations control actions may be produced upon polarized light by the use of the vibrations of piezo-electric 5 crystals, with the result that the color or the intensity or brightness of the light is varied at the rhythm of the modulations as has been set forth in patent application Serial No. 171,583, filed February 28, 1927, by 10 Alexander Meissner. The action thus brought upon the polarized light takes place upon passage of light through the quartz by virtue of the resultant optical anisotropy, or else the oscillating quartz crystal serves 15 merely as the exciter of anisotropy in other media subject to the penetration of light, for instance, glass, by the mechanical transmission oscillations. The invention refers to all of these arrangements and schemes. The 20 basic idea of the invention is as follows:

In order to cause the quartz crystal to oscillate, it has heretofore been necessary to have at disposal a separate highly constant radio frequency source, being mostly in the 25 shape of a small tube generator supplying a wave equal to the natural period of oscillation of the quartz crystal. In order to avoid this complication, the present invention which is particularly useful and adapted 30 for short-wave work in transmission operates in this manner that from the high-frequency, by virtue of interference, heterodyne or beat action, the exciting frequency of the quartz crystal is directly obtained and is further 35 amplified as such, until the oscillation amplitude is raised to a point for adequate excitation of the quartz crystal. Since means adapted to far-reaching amplification of radio frequency energy without incurring the 40 risk of self-oscillations are now known (for instance, neutrodyne circuits, compensation arrangements, etc.), the basic idea of the invention is performable without any difficulties. The frequency obtained by heterodyne 45 action equals the natural period of the quartz crystal and contains directly the controlling modulations which by the aid of the light relay are changed into corresponding light variations.

50 The invention has been illustrated conven-

tionally by the accompanying drawings, wherein:

Fig. 1 illustrates a suitable form of receiving apparatus for influencing the crystal; and,

Fig. 2 illustrates conventionally a suitable form of optical system for use with a crystal of the type shown in Fig. 1.

Now referring to the drawings, signals of any character desired for reception are received by the conventionally indicated receiving means of Fig. 1, comprising an antenna 1 and a receiver 2, from which they are transferred through a transformer 3, for example, to an amplifier circuit 4 including a triode amplifier 5. Associated with the triode amplifier circuit 4 is an oscillator 6 of any desired and suitable frequency which when impressed upon the input circuit of the triode amplifier through transformer 7, 65 for example, together with the received signals produces a heterodyne beat note of a frequency suitable for vibrating or oscillating the crystal 8 which is connected with the output circuit of the triode 5, as shown, or, 70 if desired, of a different triode where a plurality of amplifiers are used. The triode 5 is arranged to amplify the exciting frequency for the crystal until the oscillation amplitude is raised to such a point that adequate 75 excitation may be obtained.

The accompanying drawings show the crystal 8 connected in the output circuit of the amplifier triode 5 across a resistance 9 and the exciting frequency is applied to the crystal 8 by means of the electrodes 10 and 10'. 80

As the exciting frequencies are applied to the crystal, the polarized light passing therethrough is doubly refracted in well known manner as shown, for example, by British Patent No. 266,753. A suitable form of optical system for an arrangement of this type is illustrated by Fig. 2, wherein light from a source 11 is directed by means of a lens 12 through a diaphragm 13 to a polarizing nicol 14. As the light polarized in one plane leaves the nicol 14 it passes through the crystal 8, and thence through the analyzing nicol 15 which polarizes the light in a direction at right angles to the plane of polarization 100

through the nicol 14, and the light issuing beyond the analyzer 15 may then be directed to the screen 16 in well known manner.

Having described my invention, I claim:—

- In combination with a radio receiving system of the type including a receiving circuit and means for impressing thereon received fluctuating signal energy together with a local means for impressing thereon an electro-motive force of a different frequency than the received fluctuating energy for producing a resultant beat note from said received energy and an amplifying means for amplifying the resultant beat note, a crystal light valve connected across the output of the amplifier for producing electric double refraction of polarized light beams passing therethrough in accordance with fluctuating potentials applied thereto from the amplifier, and a resistance coupling shunting said crystal for connecting a power supply with the plate electrode of the said amplifier, the plate circuit of said amplifier being free of extraneous inductance whereby the characteristics of said amplifier remain substantially uniform.
